(57) **CLAIM**

The ornamental design for identification bracelet (or wrist strap) with biometric detection, as shown and described.

DESCRIPTION

FIG. 1 is a perspective view illustrating my new design.

FIG. 2 is a bottom plan view thereof.

FIG. 3 is a left side elevation view thereof.

FIG. 4 is a right side elevation view thereof.

FIG. 5 is a front elevation view thereof; and,

FIG. 6 is a top plan view thereof.

No claim is made to the portions shown in dashed line.

1 Claim, 6 Drawing Sheets

FIG. 1

FIG. 2

FIG. 3

FIG. 4

FIG. 5

FIG. 6
